UNITED STATES PATENT OFFICE.

JOHN A. OLSON, OF CHICAGO, ILLINOIS.

VICE.

1,375,928.

Specification of Letters Patent. Patented Apr. 26, 1921.

Application filed September 20, 1919. Serial No. 325,244.

To all whom it may concern:

Be it known that I, JOHN A. OLSON, a citizen of the United States, residing at Chicago, in the county of Cook and State of 5 Illinois, have invented certain new and useful Improvements in Vises, of which the following is a specification.

This invention relates to machine vises and is particularly applicable to vises of this 10 character which are operated by pneumatic or other suitable power means. A vise for machines should be capable of rapid manipulation in order to open and close the same and should be adapted to exert a relatively 15 great clamping force in order to hold the work pieces securely in the jaws. My invention has these necessary or desirable features as well as various other advantages.

The objects of this invention are to provide 20 a new and improved form of vise having the above mentioned qualities; to provide a vise having simple and powerful closing mechanism; and in general, to provide such an improved construction as will be described more fully hereinafter.

In the accompanying drawings illustrating this invention:

Figure 1 is a plan view;

Fig. 2 is a side view; and,

30 Figs. 3 and 4 are sectional views showing certain details of construction.

In the preferred form, as shown in these drawings, 5 designates the main body or frame of the vise which is provided with a 35 jaw 6 having a removable false jaw or clamping member 7. A sliding jaw 8 is mounted in suitable guide-ways in the body 5 and is provided with a removable jaw 9. A cross-head or slide 10 is mounted in suitable 40 guide-ways 11 in the body 5. The slide 10 and jaw 8 are connected by means of an adjusting screw 12 whereby the opening between the jaws may be regulated. The screw 12 engages with a threaded hole 13 in the 45 jaw 8 and its opposite end is rotatably secured in the slide 10. The end 14 of the screw is squared for engagement with an adjusting wrench.

The lever or toggle mechanism for operating 50 the slide 10 constitutes one of the principal features of this invention. This slide has a downwardly extending lug or projection 15 which is provided with a hardened pressure plate 16 having a semicircular recess 17 for engagement with the correspondingly shaped end of a toggle arm 18. This

arm is connected to the slide or cross-head by means of a pin 19 so that the slide will be pulled backwardly by the arm to open the jaws. The opposite end of the arm 18 60 is pivoted at 20 to a lever 21. One end of this lever has a pin 22 which projects downwardly into a block 23 which is secured in the lower part of the body 5. The hole 24 which receives the pin is somewhat elongated so that the pin may travel in the block. The adjacent end of the lever 21 has a recess 25 which is adapted to engage with the free end of an arm 26. The opposite end of the arm 26 fits in a recess 27 in a hardened 70 block 28 which is secured in the end of the body 5. Although the pressure is exerted against this block, a pin 29 is provided as a pivot for the arm 26 in order to prevent its displacement. A second pin 30 serves as a 75 stop for the arm so as to hold it in position to insure its being engaged by the end of the lever 21.

The lever 21 may be actuated by any suitable means, but is shown as being pivoted at 80 31 to the free end of an arm 32, the opposite end of this arm being pivoted at 33 to a slide 34. This slide moves in a guide-way 35 and is connected to the piston rod 36 of a piston 37 in a cylinder 38.

The cylinder may be provided with any suitable means for regulating the inlet and exhaust of air therefrom.

The piston 37 moves to the right, as seen in Fig. 1, to actuate the jaw closing mechanism. This causes the arm 32 to swing the lever 21 on its fulcrum or pivot 22 and simultaneously causes the arm 18 to press against the cross head or slide 10 and move it forwardly. This gives a relatively 90 fast initial closing movement, but as the jaws approach their final clamping position, the outer end of the lever 21 engages with the short arm 26 and swings the free end of the arm downwardly. This 100 causes the lever 21 to be forced forwardly, this movement being permitted by the elongated hole 24. This combined thrust, toggle and lever action produces an exceedingly great clamping force with comparatively small pressure in the cylinder. Furthermore, the action is such that the opening and closing movement of the jaws to wide position which is desirable for inserting the work pieces, is rapidly effected. The arrangement whereby a slide is provided to 110 which the power may be applied and which

is connected by suitable adjusting means, such as the adjusting screw, to the movable jaw also furnishes one of the desirable features of this invention.

5 It will be noted that my improved vise may be changed in order to be adapted for different machines or uses, without departing from the spirit of this invention and therefore I do not wish to be limited to the 10 construction and arrangement as shown, except as specified in the following claims in which I claim:

15 1. In a machine vise, the combination of a body portion having a fixed jaw, a slide- able jaw mounted on said body, a slide mounted on said body adjacent to the slide- able jaw, adjusting means between the slide and slideable jaw, a lever having a movable pivot connection with the body, an 20 arm pivoted to said lever and engaging with the slide, an arm pivotally mounted in the body adjacent to the pivoted end of said lever and adapted to engage with the corresponding end of the lever to form a 25 toggle when the lever has reached a pre- determined position, and means for actuating said lever, the arrangement being such that when the lever approaches alignment with the center of the body, the arms will 30 co-act with the lever to force the slide forwardly.

35 2. Actuating mechanism for a vise, comprising a lever having a slideable pivot connection at one end, with a fixed portion of the vise, and having a recess in the adjacent end thereof, a swinging arm having one end engaging with a fixed abutment and the other end arranged to engage with said recess when the lever has reached a pre- 40 determined position, an arm pivoted to said lever and engaging with a movable portion

of the vise, and means for actuating said lever.

3. Actuating mechanism for a vise having a movable jaw, comprising two co-acting toggles, constructed so that one toggle performs the principal closing movement of the jaw while the other toggle co-acts to perform the final closing or clamping movement. 45

4. The combination of a vise body having a stationary jaw, a movable jaw mounted on said body, a cross-head mounted on said body, an adjusting screw between said cross- head and movable jaw, two toggles for actuating said cross-head, one of said toggles 50 acting in advance of the other for performing the closing movement and both toggles coacting in the final closing action, an air cylinder, and means for actuating the toggles from the cylinder. 55

60 5. In a vise, the combination of a body having a stationary jaw, guide-ways in said body, a slideable jaw mounted in said guide-ways, a cross-head mounted in said guide-ways, an adjusting screw for connecting the slideable jaw and cross-head, a projection on said cross-head, an arm pivotally connected with said projection, a lever provided with a recess pivotally connected with said arm, a pivot in one end of 65 said lever which engages with a slot in the body, a short swinging arm having one end engaging with an abutment in said body and the other end adapted to engage with said recess in the end of the lever to move the 70 lever forwardly when it is swung to a pre- determined position, a slide, an arm connecting said slide with the opposite end of the lever and pneumatic means for actuating said slide. 75

JOHN A. OLSON.
